(57) **CLAIM**

The ornamental design for a wall vase holding bracket and rosette combination, as shown and described.

DESCRIPTION

FIG. 1 is a top, front, left side perspective view of a wall vase holding bracket and rosette combination showing my new design;

FIG. 2 is a front view thereof;

FIG. 3 is a back view thereof;

FIG. 4 is a right side view thereof, the left side being a mirror image thereof;

FIG. 5 is a top view thereof; and,

FIG. 6 is a bottom view thereof.

The broken line showing on the front face of the wall vase holding bracket and rosette combination does not form a part of the claimed design.
